(57) CLAIM

The ornamental design for a garment, as shown and described.

DESCRIPTION

FIG. 1 is a perspective view of a front, top, and left side of an ornamental design for a garment in a first configuration; FIG. 2 is a front elevational view of the garment of FIG. 1; FIG. 3 is a rear elevational view of the garment of FIG. 1; FIG. 4 is a right side elevational view of the garment of FIG. 1;

FIG. 5 is a left side elevational view of the garment of FIG. 1;

FIG. 6 is an enlarged perspective view of a front, top, and left side of a portion of the garment of FIG. 1;

FIG. 8 is a perspective view of a front, top, and left side of the garment of FIG. 1 in a second configuration; and, FIG. 9 is an enlarged perspective view of a front, top, and left side of a portion of the garment of FIG. 8.

The evenly dashed broken lines crossing claimed surfaces depict claimed stitching. All other broken lines depict the cut lines of the enlarged and sectional views and form no part of the claim. The stippling in the figures illustrates a contrast to other claimed portions of the figures, but is not limited to a specific color, material, or texture.
